CLOSURE FOR JARS AND THE LIKE

Lindsay Thorne Crabbe, Chicago, Ill., assignor to
Phoenix Metal Cap Co. Inc., Chicago, Ill., a corporation of New York

Application February 15, 1941, Serial No. 379,141

1 Claim. (Cl. 215—43)

The invention relates to new and useful improvements in a closure for jars and the like, and more particularly to a closure of the type wherein a sealing disk is held in sealing engagement with the jar lip by a metal cap having a detachable connection with the jar.

An object of the invention is to provide a jar cap and sealing disk of the above type which are so constructed that the cap normally holds the sealing disk in contact with the sealing lip all the way across the same, and wherein said sealing disk is permitted, under excessive internal gas pressure, to flex outwardly away from the sealing lip and thus reduce the seal between the disk and the jar lip to substantially a line contact to facilitate venting.

In the drawing which shows by way of illustration one embodiment of the invention—

Figure 1 is an enlarged sectional view showing a jar cap and a sealing disk embodying the invention prior to the attachment of the cap to the jar;

Fig. 2 is a view showing the cap attached to the jar and the sealing disk held in normal sealing engagement with the jar lip, and

Fig. 3 is a view similar to Figure 2, but showing the effect of excessive internal gas pressure on the sealing disk.

The present invention has to do with a jar closure which includes a sealing disk extending across the mouth of the jar and overlying the sealing lip thereof, and a metal cap which holds the sealing disk in sealing contact with the jar. The closure cap is preferably made of metal and is provided with a depending skirt and a dome-shaped top portion which extends all the way across from one side of the skirt to the other. The skirt is provided with any suitable means for securing the same to the jar. The sealing disk which is placed in the cap may be made of any suitable gasket material, and is so dimensioned that it extends all the way across the mouth of the jar and overlies the sealing lip thereof. This sealing disk before it is placed in the cap is die-shaped so that it curves away from the dome-shaped portion of the cap. When the cap is applied, the sealing disk will contact with the lip all the way across so as to make a very efficient seal for the jar. The top of the cap being dome-shaped, curves outwardly away from the inner portion of the sealing lip of the jar and contacts solely with the sealing disk in the region directly over the outer portion of the lip.

If gas evolves from the contents of the jar so as to produce an excessive pressure, the sealing

disk will be caused to flex outwardly into contact with the dome of the cap, and this will separate the sealing disk from the inner portion of the lip, and reduce the seal between the disk and the lip to a substantial line contact adjacent the outer portion of the sealing lip. This will permit the gases to wedge in between the sealing lip and the sealing disk and force an escape through the line contact between the sealing disk and the lip, notwithstanding that the contact is a complete circumferential line contact.

Referring more in detail to the drawing, the jar closure includes a metal cap having a depending skirt 1 and a top portion 2 which is dome-shaped, said dome extending all the way from one side of the skirt to the other. The depending skirt 1 is rolled inward so as to form a strengthening bead 3, and the lower portion of the skirt is shaped as shown in the illustrated embodiment of the invention so as to provide a thread 4 which is adapted to engage threads 5 on the neck 6 of the jar for securing the cap to the jar.

Located within the metal cap is a sealing disk 7 which may be made of any suitable gasket material, and the sealing disk may be provided with any suitable protective coating on the inner face thereof as indicated at 8. This sealing disk before it is placed in the cap is die-shaped so as to give a convex shape to the disk. The sealing disk thus shaped is placed in the cap and will be retained therein in the usual manner.

The container may be of any desired construction and is referred to as a jar without any thought of limiting the invention in its use. Whatever the container may be, it is provided with a neck portion to which a cap may be attached. Surrounding the mouth of the jar is a sealing lip 9. When the closure cap is applied to the jar, the sealing disk 7 extends across the mouth of the jar and overlies the sealing lip, contacting therewith all the way across the same, as shown in Figure 2. The top portion 2 of the cap is dome-shaped as above noted, and the dome is unusually high so that the portions thereof indicated at 2a which are directly above the sealing lip, curve outwardly away from the sealing lip. As a result, when the cap is screwed on to the jar, this top portion 2 will contact with the sealing disk and press it firmly against the sealing lip. The pressure exerted against the sealing disk by the cap is in the region directly over the outer portion of the sealing lip, but this will force the sealing disk which normally curves inwardly into the mouth of the jar, firmly against

the sealing lip of the jar all the way across the same.

Let us assume that the contents of the jar evolves a gas, and that the pressure of the gas becomes excessive, so that the jar is likely to be disrupted. This gas pressure against the inner face of the sealing disk will flex said sealing disk outward, forcing it into contact with the inner face of the dome of the cap. Said disk, as noted above, is normally curved downwardly away from the top of the cap, and therefore, it will curve into the mouth of the jar to a slight extent. This die-shaping of the disk stretches the disk so that it can flex from this inwardly curved position to the outwardly curved position against the dome of the cap under the pressure of the gases. When the disk is forced to the position shown in Figure 3, by the excessive pressure of the gases within the jar, the disk is moved away from the inner portion of the sealing lip and this reduces the seal to more or less of a line contact adjacent the outer portion of the sealing lip. The gases will wedge their way in between the sealing disk and the sealing lip and will compress the sealing disk even at the line of maximum pressure thereagainst by the cap, so that the gases under this excessive pressure can force an escape through the sealing line between the disk and the lip, notwithstanding that this sealing line is a complete circumferential line contact. While the gases are thus permitted to escape, venting the jar so as to prevent disrupting the same, the seal is maintained against any possible entrance of air into the jar.

While the cap is secured to the jar by a thread as illustrated, it will be understood that it may be secured in any desired way whereby the cap

may be drawn into tight sealing engagement with the jar. While the cap is described as made of metal, it may be made of any suitable material, and minor changes in the details of construction and the shaping of the parts may be made without departing from the spirit of the invention as set forth in the appended claim.

Having thus described the invention, what I claim as new and desire to secure by Letters 10 Patent, is:

A closure for containers comprising a cap having a depending skirt adapted to be secured to the container and including a substantially rigid top portion, the inner diameter of the skirt 15 portion of the cap being greater than the outer diameter of the sealing lip of the container, a sealing disk disposed within the cap and extending across the mouth of the container and contacting with the depending skirt 20 of the cap so that said sealing disk overlies and extends beyond the sealing lip of the container, said top portion of the cap being domed outwardly from the top of the skirt at one side thereof to the other so as to contact with the 25 said sealing disk only directly over the outer edge of the sealing lip, said sealing disk being pre-formed so as to initially curve inwardly away from the inner surface of the dome-shaped top and into contact with the entire sealing surface 30 of the sealing lip, said sealing disk being adapted to flex outwardly under excessive internal gas pressure and move out of contact with the inner surface of the sealing lip of the container so as to reduce the sealing area between the disk and the sealing lip to substantially line contact at 35 the outer edge of the sealing lip.

LINDSAY THORNE CRABBE.
